UNITED STATES PATENT OFFICE.

HENRY H. MERCER, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

CHANNELING-MACHINE.

1,269,295.

Specification of Letters Patent. Patented June 11, 1918.

Application filed June 17, 1912. Serial No. 704,052.

To all whom it may concern:

Be it known that I, HENRY H. MERCER, a citizen of the United States, and a resident of Claremont, county of Sullivan, State of New Hampshire, (whose post-office address is Claremont, New Hampshire,) have invented an Improvement in Channeling-Machines, of which the following description, in connection with the accompanying drawings, is a specification, like characters on the drawings representing like parts.

This invention relates to channeling machines and more particularly to track channeling machines. Its object is to provide means for making a quick adjustment of the channeling tool from one side of the track to the other so that without the necessity of shifting the trackway itself there can be cut in the stone a second channel groove parallel to the first.

The trackway for a channeling machine is customarily formed of connected sections composed each of parallel united rails, the sections being laid to form a continuous straight trackway and brought to a level or into alinement by means of blocks placed beneath the rails.

The labor of shifting such a trackway and adjusting it to a new position forms a very large proportion of the labor involved in the channeling operation. This is especially the case with modern high powered channeling machines where the machines, and consequently the trackway, are very heavy and cumbersome; and is also especially the case in channeling relatively soft stone where the cut is quickly made, while the shifting of the trackway requires the same amount of time and labor.

The object of the present invention is to provide means whereby the channeling tool may be easily and expeditiously reversed in its relation to the trackway so that after completing a channel groove at one side of the trackway it may be caused at will to overhang the opposite side of the trackway and cut a second parallel channel groove thereat. The number of times the trackway must be shifted, blocked up and placed in alinement is thereby reduced one-half, it being necessary to move the trackway once only for each two cuts. This materially reduces the time and expense of the channeling operation.

The invention will be best understood by reference to the following description when taken in connection with the accompanying illustration of one specific embodiment thereof, while its scope will be more particularly pointed out in the appended claims.

In the drawings:

Figure 1 shows in end elevation a channeling machine with its trackway, embodying one form of the invention;

Fig. 2 is a section taken transversely through the truck support of the channeling machine in Fig. 1, such section being on the line 2—2 in Fig. 3;

Fig. 3 is a plan view of the channeling machine shown in Fig. 1, the standard being shown in section and the cutting appliances being removed;

Fig. 4 is a section on the line 4—4 in Fig. 3 showing the underlying fixed truck support and the overlying movable and reversible platform support.

Referring to the drawings and to the embodiment of the invention therein illustrated, I have shown a track channeler carrying the usual gang 5 of channeling tools mounted upon the truck wheels 6, the latter adapted to move along the usual rails 7 which, when united into connected sections to form a portable trackway, are customarily laid along the quarry bottom. Herein the truck wheels are mounted upon axles 8 which carry a lower or underlying main truck support 9 constituting a member having a fixed relation to opposite sides of the trackway. That is to say, although the relation of the tool gang and tool actuating parts to be described is reversed with reference to the trackway in cutting the second or parallel groove, the relation of the truck support to the trackway remains unchanged.

Any suitable means for propelling the channeler may be employed, but herein each axle is provided with a worm gear 10 driven by a worm 11 mounted upon the worm shaft 12. Beveled gears 13 and 14 are provided, operatively related to the worm shaft, such gears being driven in opposite directions by means of the intermeshing gear 15 on the main truck driving shaft 16. By means of clutch devices 17 and 18 of well known construction the worm shaft may be connected to either driving gear 13 or 14, while the remaining gear is disconnected, or both gears

may be disconnected, whereby the truck may be driven in one direction or the other, or held at rest.

To control the movement of the truck a member 19 is provided, adjustable on the shaft 20, said shaft carrying yokes 21 and 22 adapted to control the clutches 17 and 18. The clutches are thrown into or out of engagement by means of the forked lug 23 engaging a pin 24 on the adjustable member 19, such lug being carried by the rock shaft 25 adapted to be turned by the handle 24'. The handle is removable and can be inserted in a socket 26 at either end of the shaft.

Any suitable means may be provided for turning the truck drive shaft 16, but herein I employ the main tool actuating motor 27, which latter is mounted upon the overlying platform or reversible support 28. A driving connection between the motor and the shaft is provided by means of the sprocket chain 29 passing over a sprocket wheel on the end of the motor driven shaft 30 and a second sprocket wheel on the end of the truck drive shaft 16. The truck drive shaft is mounted in a removable bearing member 31 and when the position of the platform support 28 is reversed upon the truck support, thereby bringing the motor at the opposite side of the truck, the bearing 31 is removed and bolted in a reverse position at the opposite end of the depression in the truck support in which it is located, thereby permitting the same driving connections to be maintained between the driving motor and the truck driving shafts.

The top surface of the truck support is given a grid-like formation to enable the operative to slide the platform support 28 about on the same by means of a crowbar or other lever-like implement and the truck driving mechanism, including the truck driving shaft 16, worm shafts 12, and power-transmitting connections, are contained in trough-like depressions below the said grid-like surface, thereby presenting no parts projecting above the surface to interfere with the movement of the platform support 28 over the same.

The operative mechanism of the cutting appliances is carried upon the reversible platform support 28. Such mechanism may be of any suitable type, but herein for illustrative purposes I have shown a channeler of the pulsator type wherein a pulsator 32 driven by the electric motor 27 has the opposite ends of its cylinder connected by the pipes 33 and 34 to opposite ends respectively of the working cylinder 35, the piston of which is connected to reciprocate the tool gang 5. As is well known in this class of apparatus, the alternate compression and rarefaction of air or other pressure fluid in the opposite ends of the pulsator cylinder causes a corresponding alternate compres-

sion and rarefaction in opposite ends of the working cylinder and the rapid reciprocation of the channeling gang. While, for purposes of illustration, I have shown my invention in connection with a channeler 70 of this type, it may be applied with facility and advantage to channeling machines of other types and having cutting appliances operated by other devices.

Herein the motor 27 is mounted at one 75 end of the platform support 28 and drives the crank shaft of the pulsator through speed reduction gearing comprising the pinion 36 on the motor shaft meshing with the driven gear 37 on the crank shaft of the 80 pulsator. To drive the transmission shaft 30 for the truck driving mechanism, the crank shaft carries the pinion 38 meshing with the gear 39 on the shaft 30.

The opposite end of the platform sup- 85 port 28 from the motor 27 is provided with an upturned face 40 to which there is bolted the upright tool support or standard 41. The latter is of the usual formation having guideways on which there is adjustably 90 mounted a sliding frame composed of the working cylinder 35 and the cross head guides 42, the latter serving to guide the cross head 43 which connects the tool gang 95 to the piston rod 44.

To raise or lower the frame and advance the cutting appliances toward or retract the same from the work, the standard carries the feed screw 45, the lower end of which has connection to the sliding frame, while 100 the upper end passes through a nut or other threaded member on the standard and fixed to turn with the gear 48.

Herein mechanism for turning the gear and nut, thereby to feed the tools, is also 105 mounted upon the reversible support 28, the same including connections between the gear and the motor whereby the feed-screw may be fed by power in either direction at will.

For this purpose there is provided the 110 upright shaft 46 journaled in bearings attached to the standard and carrying at its upper end the gear 47 which meshes with the gear 48 on the feed screw. The lower end of the shaft 46 carries beveled gears 115 49 and 50 which are adapted each to be separately clutched to or unclutched from the shaft 46 by means of clutches 51 and 52 similar to the clutches 17 and 18 and controlled by the clutch operating handle 53. 120 The gears 49 and 50 are simultaneously turned in opposite directions by the beveled gear 54 carried on the end of the pulsator crank shaft and constantly driven, therefore, by the tool actuating motor 27. By 125 throwing the handle 53 the sliding frame may be advanced on the standard toward the work or withdrawn from the same, or held at rest. Devices for bracing the standard are preferably employed, such as one or 130

more brace rods 55 attached at one end to the upper part of the standard and at the opposite end to the reversible support 28.

The reversible platform support 28 is held 5 by any suitable means in fixed position at one end or the other of the truck support and in such relation thereto as to hold the tool gang in overhanging relation to the trackway at one side thereof. Herein there 10 is provided at each side of the truck support 9 and adjacent to and parallel to the edge thereof a T-slot 56. This slot is adapted to receive the heads of the clamping bolts 57, which bolts lie in vertical grooves 58 in 15 the sides of the platform support 28, whereby by the application of clamping nuts to the threaded ends of the bolts the platform support may be clamped in fixed position with the grooves alining with the T-slots. 20 It will be observed that the platform support may be fixed on the truck support with the standard at either end thereof or at any intermediate position, since the T-slot 56 extends for the entire length of the truck 25 support. The standard may also be reversed by reversing the platform support and clamping the latter in the T-slot 56 at the opposite side of the truck support, thereby permitting the channeler to be operated 30 with the tool overhanging the opposite side of the trackway and with the standard fixed at either end of the truck.

To shift the standard to either end or either side of the truck, the bolts 57 are 35 loosened and withdrawn from the slots and the platform support is slid around upon the truck support until the desired position is reached with the grooves 58 in alinement with the slots 56, whereupon it is again 40 clamped fixedly in position. The gridded surface of the truck support presents a succession of pockets into which the ends of the workman's crowbar can be placed and the platform support easily moved from one 45 point to another under the leverage of the bar. This is also facilitated by forming the support 28 with a succession of depressions 59, as shown in Figs. 1 and 4, which project beyond the intermediate lower limits 50 of the support, whereby leverage can always be obtained by a crowbar inserted in one of the pockets and applied to the walls of the support.

The tool actuating devices, including the 55 tool feeding mechanism, being self-contained upon the reversible support, and the truck driving connections being reversible with the support, the channeler can be operated as readily in one position with reference to 60 the trackway as in its reverse relation to the trackway. The length of overhang of the tool gang from the truck determines the width of the block where the tool appliances are reversed for cutting the second parallel 65 groove. In order that different widths of

blocks may be cut with the same apparatus, some provision is preferably made whereby the length of this overhang can be varied as may be required. This may be accomplished 70 in any suitable or convenient way, but herein I have provided by way of illustration additional grooves 60 in the sides of the platform support 28 whereby such platform support can be adjusted in different positions transversely of the truck, and the 75 length of tool overhang thereby varied. Two sets only of such vertical grooves are herein shown for purposes of illustration, but it will be evident that any number may be provided or any other suitable means employed for securing a suitably graduated adjustment to any desired extent of the tool 80 overhang.

When the overhang is varied, suitable means may be provided for maintaining the 85 alinement of the driving and driven sprocket members, such as a sprocket wheel member on one or the other of the two shafts 16 or 30 having an extended hub so as to maintain the alinement of its sprocket wheel with 90 the other sprocket wheel.

While I have herein shown and described for purposes of illustration one specific embodiment of the invention, it is to be understood that extensive deviations may be 95 made from the structure therein shown without departing from the spirit thereof.

Claims:

1. In a channeler, a truck having a plane upper surface, a platform support slidable 100 on said surface, channel cutting mechanism on said platform support including an overhanging tool and an operatively connected motor, and truck driving mechanism operatively connectible with said motor when 105 said tool overhangs either side of said truck.

2. In a channeler, a truck having a plane upper surface, a platform support slidable on said surface, channel cutting mechanism on said platform support including an overhanging tool and an operatively connected motor, and truck driving mechanism operatively connectible with said motor when 110 said tool overhangs the side of said truck at either end thereof.

3. In a channeler, a truck having a plane upper surface, a platform support slidable on said surface, channel cutting mechanism on said platform support including an overhanging tool and an operatively connected 120 motor, and truck driving mechanism operatively connectible with said motor when said tool overhangs either side of said truck at either end thereof.

4. In a channeler, a truck having a plane 125 upper surface, a platform support slidable on said surface, channel cutting mechanism carried on said support including a tool and an operatively connected motor, and truck driving mechanism operatively connected to 130

said motor and including a driving connection disposed intermediate the ends of said truck and beneath the surface thereof.

5. In a channeler, a truck having a plane 5 upper surface, a platform support slidable on said surface, channel cutting mechanism carried on said truck including a tool and an operatively connected motor, and truck driving mechanism operatively connected to 10 said motor and including a bodily reversible driving connection disposed intermediate the ends of said truck and beneath the surface thereof.

6. In a channeler, a truck having a plane 15 surface, a platform support slidable into position parallel to either end of said surface, channel cutting mechanism on said support including a tool and an operatively connected motor, and truck driving mechanism disposed between the operative positions of said support and operatively connectible to said motor in either of said positions.

7. In a channeler, a truck having a plane 25 upper surface, a platform support slidable into a plurality of reverse positions at each end of said surface, channel cutting mechanism on said support including a tool and an operatively connected motor, and truck driving mechanism including a bodily 30 reversible connection disposed between the operative positions of said support and operatively connectible to said motor.

8. In a channeler, a truck having a plane 35 upper surface, a platform support disposable in a plurality of reverse positions at one end thereof, channel cutting mechanism on said support including a tool and an operatively connected motor, and truck driving mechanism operatively connectible to said 40 motor including a reversible driving connection disposable in a plurality of reverse positions beneath said surface.

9. In a channeler, a truck having a plane 45 upper surface; an elongated platform support slidable thereon; channel cutting mechanism including a tool, a pulsator, and a motor operatively connected and disposed

in substantial alignment on said support; and truck driving mechanism operatively connectible to said motor when said support 50 is located on either side of the transverse center line of said truck.

10. In a channeler, a truck having a plane 55 upper surface provided with a transverse depression intermediate its ends, a platform support slidably mounted on said surface, channel cutting mechanism carried on said support including a tool and an operatively connected motor, truck driving mechanism including a shaft reversibly mounted in said 60 depression, and operative connections between said shaft and said motor.

11. In a channeler, a truck having a plane 65 upper surface, a platform support slidable on said surface, channel cutting mechanism on said platform including an overhanging tool and an operatively connected motor, means for locking said support to said truck in a plurality of positions, and truck driving mechanism operatively connected to said 70 motor when said tool overhangs either side of said truck at either end thereof.

12. In a channeler, a truck having a plane 75 upper surface, a platform support slidable thereon and disposable in a plurality of reverse positions at either end of said surface, each substantially parallel to the end of said truck, channel cutting mechanism on said platform support including a tool and an operatively connected motor, and truck driv- 80 ing mechanism operatively connectible to said motor in any operative position of said support including a reversible driving connection disposable in a plurality of reverse positions beneath the surface of said truck 85 at a point intermediate the ends thereof.

In testimony whereof, I have signed my name to this specification, in the presence of two subscribing witnesses.

HENRY H. MERCER.
